UNITED STATES PATENT OFFICE

2,349,666

PERFORATOR GUN WITH IMPROVED
PROJECTILE RESTRAINING MEANS

Ira J. McCullough, Los Angeles, Calif.

Application February 10, 1940, Serial No. 310,296

26 Claims. (Cl. 164—0.5)

My present invention relates to means for perforating casing and relates in particular to a gun for shooting projectiles through the wall of a casing set in a well, such gun employing my new and improved method and means for delaying initial movement of the projectile, and wherein economy of gun manufacture, economy of upkeep, and superior perforating results are obtained.

It is an object of the present invention to provide a perforating gun wherein a greater length of gun bore and greater velocity of projectile are obtained in a gun of a given diameter, as compared to guns which have been previously employed for this purpose. In many instances the production of a well is carried to the surface of the ground through an oil tube consisting of a string of pipe of much smaller diameter than the well casing ordinarily employed. I find that one of the results obtainable in the use of my present invention is the reduction of the overall diameter of an effective perforating gun to such size that the gun may be lowered through an oil tube which has been set in a well to the position at which it is desired to perforate the casing, thereby avoiding the necessity of pulling the oil tube from the well.

It is a further object of the invention to provide a gun which is relatively cheap, or of low cost of manufacture, wherein economy of manufacture, upkeep, and operating costs are maintained without sacrifice of efficiency of operation, and in fact enabling a greater efficiency of operation than is obtainable from many of the previous types of perforating guns of comparatively high manufacture, upkeep, and operation costs.

A further object of the invention is to provide a perforating gun having a simplified form of projectile delaying means, whereby the invention avoids the use of the previously employed relatively expensive projectile delaying means. For example, to hold the bullet stationary for a time after ignition of the firing charge in the powder chamber of the previous types of gun so as to build up the propelling gas pressure before release and discharge of the projectile, it has been the practice to employ collars or flanges on the projectiles or shear plates disposed adjacent the rear end of the projectiles. In my present invention I eliminate such restraining means, and due to the use of a simplified form of means for delaying initial movement of the projectile, I am enabled to employ a projectile of simple cylindrical form without projecting flanges or collars, and to use such projectile in such manner that

a high muzzle velocity is obtained and accordingly efficient penetration of the well casing is accomplished.

It is an object of the invention to provide means in a perforating gun for delaying the initial movement of a projectile disposed in the gun bore, by retarding the building up of propelling gas pressure adjacent the rear end face of the projectile immediately after ignition of a firing charge in the firing charge chamber associated with the gun bore, so that the projectile will be discharged under force of a large volume of propelling gas at an effectively high pressure.

It is an object of the invention to provide a perforating gun having a wall in such spaced relation to the rear end of the projectile disposed in the gun bore, that the building up of a propelling gas pressure adjacent the rear face of the projectile is retarded and an effective delay of the movement of the projectile is thereby obtained.

A further object is to provide a gun and projectile assembly wherein the gun bore is so placed relative to other walls of the gun that a projectile in such gun bore has a side wall exposed to the initial gas pressure obtained from the burning of a firing charge in the firing charge chamber of the gun, and whereby an effective delay of the movement of the projectile is obtained.

30 Further objects and advantages of the invention will be brought out in the following part of the specification.

Referring to the drawing which is for illustrative purposes only:

35 Fig. 1 is a view, sectioned on a vertical plane of a gun embodying a preferred form of the invention.

Fig. 2 is a fragmentary sectional view showing an alternative form of the projectile delay means as applied to a multiple firing arrangement.

40 Fig. 3 is a fragmentary sectional view showing an alternative form of projectile delay or restraining means.

Fig. 4 is a fragmentary section showing the rear end of a gun bore with the bullet removed therefrom.

45 Fig. 5 is an enlarged fragmentary section similar to Fig. 4 to show a space adjacent the rear end of the bullet.

In Fig. 1 I show a gun body 10 comprising a suspension member 11 and a plurality of gun body sections 12 and 13 secured together in axial relation by threaded joints 15 individually identified as 15a, 15b, and 15c. The top or suspension member 11 carries a firing pin 16 in an axial

opening 17, to engage, when driven down, a priming element 18 comprising a cartridge carried in a removable cylindrical block 19 seated in a counterbore 20 in a position above an ignition charge chamber 21. The joint 15a between the suspension member 11 and the body section 12 comprises a threaded pin 22 which extends down from the suspension member 11 into a threaded box 23. The primer block 19 is disposed in the counterbore 20 which extends down from the bottom of the threaded box 23 so that when the joint 15a is unscrewed, the block 19 may be removed, thereby exposing the firing charge chamber 21 for the placing of an ignition charge 24 therein, and at which time a new primer 18 may be placed in the block 19. From the ignition charge chamber 21 a passage of small diameter 26 extends down through a replaceable restraining member 39, threaded in the pin 27 of the joint 15b, to communicate with a firing charge chamber 28 projecting downward in the body section 13 from the bottom of the threaded box 29 of the joint 15b, thus being in such position that unscrewing of this joint 15b will expose the chamber 28 for recharging, as by placing therein a charge of powder 30 constituting the firing charge.

From one side of the body 13 an opening extends inward so as to form a gun bore 31. The firing charge chamber 28 communicates with the inner end of the gun bore 31 through a passage 33 of such large diameter that the gas from the burning of the charge 30 may readily pass therethrough. It will be noted that the firing charge chamber 28 lies to one side of the gun bore 31 so that the inner end of the gun bore 31 can be disposed relatively near to the external face of the body section 13 opposite from the external mouth of the gun bore 31. Accordingly, the rear end face 34 of a projectile 35 placed in the gun bore 31 as shown, will lie at a distance from the mouth 36 of the gun bore 31 considerably greater than the radial dimension of the gun body. In view of this, it is possible to keep the projectile under direct pressure of propelling gases while it is traveling through a considerable distance as compared to the diameter of the gun body, thereby obtaining a high muzzle velocity for a gun having a given body diameter.

From the inner end portion of the gun bore 31 a passage 37 extends downward to the lower end face of the pin 40 forming the joint 15c by which consecutive sections 13 are joined, this passage 37 having a threaded portion 38 to receive a restraining means 39 of replaceable type having a small diameter passage 39a therethrough communicating with a succeeding firing charge chamber 28 formed in the succeeding gun body section 13 which is substantially a duplicate of the section 13 described in detail, with the exception that the gun bore 31 therein is faced in another direction from that of the gun bore in the upper section 13. Sealing means are provided to prevent entry of water into the interior of the gun body, such sealing means including packing 49 around the firing pin 16 and sealing members 50 placed in the gun bores 31 and 45 adjacent the outer ends of the projectiles 35 and 46. The sealing means 50 may consist of rubber cups which are forced into the gun bores into the position shown or may consist of a sealing material placed in position and allowed to harden therein. The packing 49 is forced into sealing engagement with the firing pin 16 by threaded plugs 52 which are

screwed into diametrically disposed threaded openings 53.

As hereinbefore indicated a principle of my invention consists in delaying the initial movement of the projectile from the gun body without the use on the bullet of shoulders, flanges or plates which by the shearing or deforming strength thereof delay the movement of projectiles until the propelling gas pressure has built up to a desired extent. It will be noted that the projectile 35 is essentially cylindrical and may be readily machined from suitable material such as steel. In the form of the invention shown in gun body section 13, a wall 54 is provided in a position adjacent to, and in some instances in contact with, the rear end face 34 of the projectile 35. When the priming element 18 is set off as a result of the firing pin 16 being driven downward into engagement therewith, the ignition charge 24 will be ignited and heat and/or pressure produced in the chamber 21 will be transmitted through the passage 26 to the chamber 28 to ignite the firing charge 30. The propelling gases resulting from the ignition of the charge 30 are transmitted through the communicating passage 33 to the inner end of the upper gun bore 31, and the pressure of these propelling gases rapidly builds up as the burning of the charge 30 progresses, but owing to the fact that the inner end face 34 of the projectile 35 is spaced relatively close to the wall 54 the building up of gas pressure adjacent this rear end face 34 will be retarded, and by the time sufficient pressure has built up adjacent the inner end face 34 to start outward movement of the projectile 35 a very high gas pressure will have been built up in the chamber 28, the passage 33 and the space 32 so that when the projectile 35 then moves outward in the gun bore 31 it will be propelled by a large amount of gas accumulated in highly compressed state and under high pressure in the chambers of the gun communicating with the rear end of the gun bore 31. Therefore an extremely high muzzle velocity will be attained in the projectile 35 by the time it reaches the muzzle or mouth 36 of the gun bore 31.

In the upper section 13 of Fig. 1 and in Fig. 4 I have indicated that the wall 54 may be cupped so that the peripheral portion 55 thereof may extend around an annular area of the side wall of the projectile 35. In Fig. 5, drawn to enlarged scale, I have shown a space 54' between the rear end of the bullet 35 and the wall 54 in which gas pressure may accumulate. It will be understood that this space 54' may be much less than a thousandth of an inch, and that it may consist of such space as exists when there is actual contact between the rear end face 34 of the bullet 35 and the wall 54, for the reason that in ordinary manufacturing processes the surfaces are not so perfectly formed that all portions of the walls 54 and 34 are in contact. It will be understood, however, that the wall which lies adjacent the rear end of a projectile may be flat and in fact may be spaced from the rear end face of the projectile, under which circumstances a space of restricted volume will be formed adjacent the rear end face of the projectile in which the building up of propelling gas pressure is retarded. As an example, I have in body section 14 of Fig. 2 shown that the flat wall lying adjacent the inner end face of a projectile 46 may comprise the inner end face of another projectile. It will be perceived, accordingly, that the rear end face 47 of each projectile 46 will serve as a means for

retarding the building up of pressure adjacent the rear end face of the other projectile. In Fig. 2 I have shown the existence of a space 47 between the rear end faces 47 of the bullets 46, and it will be understood that this space may vary within reasonably large limits and that it may be such space as exists when there is actual contact between the rear end faces 47.

Fig. 2 shows a firing charge chamber 41 which communicates through a passage 43 with substantially the center of a diametral bore 44 which forms a pair of gun bores 45 extending inward from the exterior of the gun body 13 and communicating with the passage 43. In each of these gun bores 45 there is a projectile 46, these projectiles 46 being positioned so that the inner end faces 47 thereof lie in such spaced relation, or in general practice substantially in engagement, that the space between the inner end faces 47 will be of such size that the desired retarding effect will be attained. A firing charge 48 is placed in the firing charge chamber 41. The propelling gas produced from the burning of the charge 48 will pass through the passage 43, and owing to the relative closeness of the rear end faces 47 of the projectiles 46 there will be a short delay in the building up of gas pressure against the rear end faces 47, during which time a heavy pressure of gas accumulates in the chamber 41 and the space 43 so that when outward movement of the projectiles 46 finally starts, these projectiles will be moved through the respective gun bores 45 by propelling gas capable of producing in the projectiles a high muzzle velocity.

In Figs. 1 and 2 I have shown forms of my invention wherein a part of the rear end of a bullet projecting into a gas space is covered, thereby accomplishing a delay in the forces which tend to hold it stationary, including inertia of the projectile and frictional resistance of the projectile and the sealing means associated therewith.

In Fig. 3 I show an alternative form of the invention wherein the covered portion of the inner end of the projectile consists of a side face of the inner end of the projectile instead of the inner end face thereof.

In this view a gun body section 13' is shown having a firing charge chamber 69, a gun bore 81, and a passage 82 connecting the chamber 69 with a side portion of the inner end of the gun bore 81. It will be noted that the interconnecting passage 82 has a mouth 83 which leads into the side wall of the bore 81. A projectile 84 of simple cylindric form is placed in the gun bore 81 in such position that the inner end portion 85 thereof projects part way across the mouth 83 of the passage 82. Accordingly, the upper face 86 of this inner end portion 85 of the projectile 84 is exposed in the mouth 83 of the passage 82, but the lower portion 87 of the side wall of the end portion 85 is covered by the inner lower portion 88 of the gun bore 81. When a firing charge is burned in the chamber 69 the blast of propelling gas under high pressure which passes downward through the passage 82 will strike directly against the exposed upper face of the inner end portion 85 of the projectile 84, forcing the rearward portion of the projectile downward tightly against the lower wall of the gun bore 81 so as to bind the projectile 84 in the gun bore, whereby to hold the projectile 84 stationary until sufficient pressure has built up against the rear end face thereof to start its outward movement in the gun bore.

In the use of the perforating assembly, shown in

Fig. 3, the fact that the projectile 84 is initially cramped in the inner end portion of the bore 81 as evidenced by the marking of the inner upper surface of the gun bore 81 at the point 90 by the front shoulder of the projectile 84.

A feature of the invention is to provide a mouth leading to the space at the rear end of the projectile through which the pressure of the explosion of the powder charge may pass into the space. This mouth may be very small at the time the powder charge is set off and increases to full size as the projectile moves outward, thereby permitting application to the rear end of the projectile the full pressure of the gases accumulated during the short time the initial movement of the projectile is retarded. Such mouth may be the mouth 83, shown in Fig. 3. One wall of this mouth is formed by the rear end of the projectile 84, and therefore its size may be decreased to nearly zero value by moving the projectile 84 rightward from the position in which it is shown. The mouth 83 being smaller in size than the diameter of the passage 82, retards the flow of gas from the firing of the powder charge into the space adjacent the rear face of the projectile 84. Then, as the projectile moves leftward, the mouth 83 increases to the full size of the lower end of the passage 82. It will be understood that in the form shown in Fig. 5 this mouth may consist merely of the narrow crack between the rear end of the projectile 35 and the peripheral wall 55, through which gas pressure may enter the space 54' adjacent the rear face of the projectile.

A further important feature of my present invention consists in the provision in a gun of this character of a chamber or space for the accumulation of propelling gases under high pressure, making it possible to use a heavy charge of explosive as compared to the strength of the walls 40 of the gun body, as a result of the cushioning effect of the chamber or space, and as the final result accomplishing a higher muzzle velocity of the projectile by reason of the application of high pressure propelling gases against the rear end face of the projectile until it reaches and leaves the muzzle of the gun bore.

It has been the previous practice to design the firing charge or powder chambers of guns of this type with relation to the quantity of powder required to propel the projectile and the strength of the chamber wall obtainable in a gun of a given diameter. Where attempts have been made to increase the strength or quantity of an explosive charge without increasing the diameter of the gun body, destruction of the gun body has resulted, or the gun barrels which are held in threaded openings have been blown out of the gun body. I find that I am able to increase the muzzle velocity for a given diameter of gun very materially by providing an accumulator for gases under high pressure prior to the discharge of the projectile. This accumulator may comprise a chamber formed in communication with the inner end of the gun bore, or in its simplest form may consist merely of an enlargement of the firing charge chamber so that the volume of the firing charge chamber will be greater than the volume of the powder charge, to an extent providing in the chamber a space which will serve as a cushion for the detonation resulting from the burning of the powder charge and for holding a volume of gas under high pressure which has resulted from the burning of the powder charge. Accordingly, the destructive effects of the detonation of the powder charge on the gun body or on

threaded joints of the gun structure is avoided, and the provision of the gas accumulator or reservoir, in conjunction with the initial delay of the projectile, enables the attaining of a high muzzle velocity of the projectile, for the reason that the propelling gases, under high pressure, are fed from the accumulator space of the gun body into the rear end of the gun bore as the projectile moves outward, maintaining an effective propelling force against the rear end face of the projectile not only during the initial movement of the projectile but as the projectile moves through the outer portion of the gun bore. It will be perceived accordingly that the firing charge chambers 28 and 41 are given a volume materially larger than the volume of the body of explosive material constituting the charges 30 and 48. In the prior practice the volume of the firing charge chamber was completely filled by the volume of the firing charge. This, of course, can be varied within working limits, depending upon the characteristics and burning speed of the explosive materials, and other factors including strength of steel employed in the gun body, size, and inertia of projectile, length of gun bore, etc.

Although I have shown and described simple and practical forms of my invention, it will be understood that certain parts or elements thereof may be replaced by other equivalent parts or elements without departing from the spirit of the invention. Accordingly, the invention is not to be limited by the details of this disclosure but should be accorded full scope of the following claims.

I claim as as my invention:

1. In a perforating means of the character described, the combination of: a projectile; a gun barrel to receive said projectile at the inner end thereof and to guide the same through its outward travel; means connected to the inner end of said barrel to supply propelling gases thereto; and wall means cooperating with the rear portion of said projectile so as to form a chamber adjacent the rear end face of said projectile, said chamber having an entrance opening for flow of propelling gas into said chamber, said entrance opening transecting said chamber in advance of its rear end wall being of such small size as to retard the building up of gas pressure in said chamber, and the walls of said entrance opening being formed in part by the rear end of said projectile so that as said projectile moves outward the size of said entrance opening will increase.

2. In a perforating means of the character described, the combination of: a projectile; a gun barrel to receive said projectile at the inner end thereof and to guide the same through its outward travel; means connected to the inner end of said barrel to apply propelling gas thereto, said means comprising walls forming a chamber communicating with said barrel; and wall means disposed in adjacent relation to the rear portion of said projectile to retard the building up of gas pressure adjacent the rear end face of said projectile to delay movement of said projectile while pressure builds up in said chamber.

3. In a perforating means of the character described, the combination of: a projectile; a gun barrel to receive said projectile at the inner end thereof and to guide the same through its outward travel; means connected to the inner end of said barrel to apply propelling gas thereto, said means comprising walls forming a chamber communicating with said barrel; and a wall disposed

in such relation to the inner end of said projectile as to retard the building up of pressure adjacent the rear end face of said projectile to delay movement of said projectile while pressure builds up in said chamber.

4. In a perforating means of the character described, the combination of: a body having a gun bore; means for applying propelling gas pressure to the inner end of said gun bore, said means comprising a firing charge chamber in communication with the inner end of said gun bore, and a wall contiguous to the inner end of said bore; a projectile in said gun bore, said projectile having an inner end face disposed in such relation to said wall that the building up of gas pressure adjacent the inner end face of the projectile will be retarded; and means for causing explosion of a firing charge disposed in said firing charge chamber.

5. In a perforating means of the character described, the combination of: a body having a gun bore; means for applying propelling gas pressure to the inner end of said gun bore, said means comprising a firing charge chamber in communication with the inner end of said gun bore, and a wall contiguous to the inner end of said bore; a projectile in said gun bore, said projectile having an inner end face disposed in such relation to said wall that the building up of gas pressure adjacent the inner end face of the projectile will be retarded; a firing charge in said firing charge chamber, said firing charge occupying such portion of said firing charge chamber that there will be left in said firing charge chamber a space of such size as to provide a cushion to absorb the initial force of the explosion and serve as an accumulator for gas under pressure prior to the discharge of said projectile from said gun bore; and means for causing explosion of said firing charge.

6. In a perforating means of the character described, the combination of: a body having a gun bore; means for applying propelling gas pressure to the inner end of said gun bore, said means comprising a firing charge chamber in communication with the inner end of said gun bore, and a wall contiguous to the inner end of said bore; a projectile in said gun bore; means operating to delay the discharge of said projectile from said gun bore, comprising a chamber formed in part by said contiguous wall and in part by the rear end of said projectile and having a mouth which increases in size as said projectile moves outward from its initial position in said bore; and means for causing explosion of a firing charge in said firing charge chamber.

7. In a perforating means of the character described, the combination of: a body having a gun bore; means for applying propelling gas pressure to the inner end of said gun bore, said means comprising chamber means to form an accumulator and a firing charge chamber in communication with the inner end of said gun bore, and a wall contiguous to the inner end of said bore; a projectile in said gun bore; means operating to delay the discharge of said projectile from said gun bore; and means for causing explosion of a firing charge in said firing charge chamber.

8. In a perforating gun of the character described, the combination of: a body having a plurality of gun bores extending inward from the outer face thereof, with the inner ends of said bores in communication; means for applying propelling gas pressure to the inner ends of said gun bores; and a plurality of projectiles one each of

which is in one of said gun bores, the inner ends of said projectiles being spaced so close together as to retard the building up of pressure adjacent the inner end faces of said projectiles.

9. In a perforating gun of the character described, the combination of: a body having a plurality of gun bores extending inward from the outer face thereof, with the inner ends of said bores in communication; walls forming a firing charge chamber having communication with the inner ends of said gun bores; a plurality of projectiles one each of which is in one of said gun bores, the inner ends of said projectiles being spaced so close together as to retard the building up of pressure adjacent the inner end faces of said projectiles; a firing charge in said firing charge chamber; and means for igniting said firing charge.

10. In a perforating means of the character described, the combination of: a projectile; walls forming a gun bore to receive said projectile; and means for applying a propelling gas to the rear end of said gun bore, said means including a firing charge chamber in which a firing charge may be burned, said firing charge chamber being so formed relative to the inner end of said gun bore that the initial pressure of gas resulting from the burning of said firing charge will be applied to a side of said projectile in said gun bore, thereby delaying movement of said projectile from its initial position in said gun bore.

11. In a perforating means of the character described, the combination of: a projectile; walls forming a gun bore to receive said projectile; and means for applying a propelling gas to the rear end of said gun bore, said means including a firing charge chamber in which a firing charge may be burned, said firing charge chamber being offset to a side of said gun bore and being connected to said gun bore by passage means so placed that the force from the burning of a firing charge in said chamber will be directed against a side portion of said projectile in said gun bore.

12. In a perforating means of the character described, the combination of: walls forming a gun bore; means for applying a propelling gas pressure to the inner portion of said gun bore, said means comprising a port opening which communicates with one side of said gun bore; and a projectile positioned in said gun bore so that a portion of its rear end projects across said port opening for the purpose of receiving from a lateral direction the initial application of said gas pressure, to bind the projectile in the gun bore and delay its outward movement.

13. In a perforating means of the character described, the combination of: walls forming a gun bore; a space communicating with the rear end of said gun bore; a projectile positioned in the gun bore so that a rear end portion of the projectile will extend into said space; delay means for said projectile comprising a wall engaging a portion of said rear end portion of said projectile so as to cover the same and leave a side portion of the projectile exposed; and means substantially instantaneously building up a propelling gas pressure in said space.

14. In a perforating means of the character described, the combination of: walls forming a gun bore; a space communicating with the rear end of said gun bore; a projectile positioned in the gun bore so that a rear end portion of the projectile will extend into said space; delay means for said projectile comprising a wall placed so as to cover a side of said rear end portion and

leave the opposite side thereof exposed; and means substantially instantaneously building up a propelling gas pressure in said space.

15. A well casing perforating gun comprising: means defining a gun bore; a bullet fitting the gun bore; means for generating an explosive pressure; means for diverting a limited portion of the explosive pressure to propel the bullet into position for full application of said explosive pressure during an initial period calculated to permit generation of the explosive pressure to a high value.

16. A well casing perforator, comprising: a gun body having a gun bore adapted to receive a bullet, and means for applying gas pressure into the gun bore at the side thereof; a bullet fitting the gun bore and positioned initially to close the gun bore to said gas pressure; and means for introducing a portion only of said gas pressure behind the bullet to move the bullet forwardly until the bullet opens said gun bore to the full gas pressure.

17. In a perforating gun, the combination of: a gun body having a gun bore adapted to receive a bullet, means for generating an explosive pressure, a port for introducing explosive pressure to the side of the gun bore, and means for diverting a limited portion of the explosive pressure to the rear of said gun bore; and a bullet fitting said gun bore and initially closing said port, said bullet being propelled initially at a comparatively low velocity under urge of the limited portion of the explosive pressure, and upon uncovering said port at a high velocity under urge of the entire explosive pressure.

18. A well casing perforating gun comprising: a gun body having a gun bore and a bullet fitting said bore; means for applying explosive pressure to said bore; and means for diverting a limited portion only of the explosive pressure against the bullet to urge it forward in the gun bore for a predetermined interval before exposing the bullet to the entire explosive pressure.

19. A well perforating gun comprising: a gun body defining a gun bore, a cartridge chamber and a passage connecting the cartridge chamber to the side of the gun bore; an explosive cartridge in the cartridge chamber; a bullet in the gun bore, the bullet positioned to separate the passage from the gun bore; and means providing restricted communication between the cartridge chamber and the base end of said bullet whereby, upon ignition of said cartridge, initial movement of the bullet along the gun barrel is impeded to permit rise of pressure in said cartridge chamber before the bullet uncovers said passage and receives the full application of said explosive pressure.

20. A well perforating gun comprising: a gun body defining a gun bore, a cartridge chamber, and a connecting passage extending laterally from the gun bore to the cartridge chamber; an explosive cartridge in said chamber; a bullet positioned in said gun bore to close said passage; the bullet and gun bore defining a restricted means of communication between the passage and the base end of the bullet to prevent full exposure to the pressures generated in the cartridge until the bullet uncovers said passage.

21. A well perforating gun comprising: a gun body defining a gun bore, a cartridge chamber and a passage extending from the cartridge chamber to a point in the side of but adjacent the inner end of the gun bore; an explosive cartridge for said cartridge chamber; a bullet

for said gun bore initially fitting against the inner end of the gun bore to restrict communication between the passage and the base end of said bullet until the bullet is moved away from the inner end of the gun bore.

22. A gun perforator comprising: a gun body defining a gun bore, a cartridge chamber and a passage extending from the cartridge chamber and intersecting the gun bore adjacent its inner end; an explosive cartridge for said cartridge chamber; a bullet for said gun bore, said bullet conforming to the inner end of the gun bore and initially positioned thereagainst, and when so positioned forming a slide valve substantially closing communication between the passage and the gun bore, there being sufficient clearance between the bullet and gun bore to permit a limited portion of the explosive pressure generated by ignition of said cartridge to leak behind the bullet and propel the bullet forwardly at low velocity until it uncovers said passage thereby to introduce a time delay period between ignition of the explosive cartridge and full application of the resulting pressure on the bullet.

23. A well perforating gun comprising: a gun body having a gun bore, an explosive chamber, and a port connecting the chamber with the side of the gun bore; a bullet positioned in the gun bore and closing said port; means sealing the bullet from contact with the liquids in which the gun body may be immersed, said means being yieldable to the pressures of said liquids to hold said bullet against the inner end of said gun bore; and means for bypassing a limited portion of the pressure generated upon ignition of said cartridge, and directing the bypassed pressure against the base of the bullet to urge the bullet

along the gun barrel in opposition to said liquid pressure until said bullet uncovers said port and is thereby exposed to the entire explosive pressure.

5 24. A method of imparting high acceleration to a bullet, characterized by: applying explosive pressure laterally into a gun bore through a port located forwardly of the inner end thereof, placing the bullet in an initial position at least partially closing communication between the gun bore and port to limit the effective application of pressure on the bullet until the bullet has moved forwardly and uncovered the port, thereby to introduce a delay between ignition of an explosive charge and full application of its pressure against the bullet.

10 25. A method of operating a gun perforator to obtain high muzzle velocity of the gun perforator bullet, characterized by: generating an explosive pressure, diverting while generating the explosive pressure, a limited portion of the pressure, propelling a bullet by the diverted portion for a period calculated to permit generation of the explosive pressure to a high value, then propelling the bullet by the fully generated force of said explosive pressure.

20 26. A method of imparting high acceleration to a bullet, characterized by: generating an explosive pressure by the burning of an explosive charge; diverting a predetermined limited portion of said explosive pressure to a bullet during the burning of the explosive charge, to move the bullet slowly from an initial position substantially unaffected by the explosive charge to a secondary position exposed to the full force of said explosive charge.

IRA J. McCULLOUGH.
